(57) **CLAIM**

The ornamental design for a vehicle underside protector, as shown and described.

DESCRIPTION

FIG. 1 is a front perspective view of the two ends of a vehicle underside protector embodying my new design; FIG. 2 is a rear perspective view thereof; FIG. 3 is a front elevation view thereof; FIG. 4 is a rear elevation view thereof; FIG. 5 is a top plan view thereof; FIG. 6 is a bottom plan view thereof; FIG. 7 is a left-side elevational view thereof; and, FIG. 8 is a right-side elevational view thereof.

In the drawings, the length of the vehicle underside protection is shown with a symbolic break in broken lines. The portions of the length shown between the broken line symbolic breaks do not form part of the claimed design.
